UNITED STATES PATENT OFFICE.

BENJAMIN F. GILBERT, OF FORT WORTH, TEXAS.

HEMSTITCHER.

Application filed September 13, 1926. Serial No. 135,079.

My invention relates to hemstitchers and more particularly to hemstitchers which can be adjustably attached to most of the sewing machines in practical service; and the 5 object is to provide hemstitchers which are simple in construction and operation and which can be furnished at small cost and which are highly efficient in doing many kinds of work. Other objects and advantages will be fully explained in the following description and the invention will be more particularly pointed out in the claims.

Reference is had to the accompanying drawings which form a part of this application.

Fig. 1 is a plan view of a hemstitcher mounted on a sewing machine table.

Fig. 2 is an edge view of the same with a presser foot of a sewing machine pressing 20 on the hemstitcher.

Fig. 3 is a plan view, showing a variation in the needle guide and spring.

Fig. 4 is an edge view of the device as shown in Fig. 1.

Fig. 5 is an edge view of the device shown in Fig. 3.

Fig. 6 is a side elevation of the device shown in Fig. 3, viewing the left side of Fig. 3.

Fig. 7 is a plan view, showing a variation in the loops.

Similar characters of reference are used to indicate the same parts throughout the several views.

This device includes two members adjustably connected together. The bed member 1 has a loop 2 for clamping the bed member 1 to the sewing machine bed by means of a set screw 3. A washer 4 which is slotted is placed on the loop 2 and then the screw 3 projected down through the washer and through the loop. The opening through the loop 2 is relatively large to permit a variety of adjustments. The bed member has two double springs 5 and 6 for holding goods to be hemstitched. The double springs 5 and 6 are duplicates and both are integral with the body 1. One member 5 of the double spring projects from the inner side of the body 1 and the other member 5' projects from the outside of the body 1 and is bent under the body and back directly under the member 5 and the ends of both come close together, the end of member 5' being curved 55 upwardly. The double spring 6 is constructed in the same manner. The large

opening through the loop permits adjustments of the hemstitcher to various types of sewing machines.

A fabric separating member is adjustably mounted on the bed or table member above described. The fabric separating member 7 has one arm 8 provided with slots 9 by which the fabric separating member 7 is adjustably attached to the table or bed member 1 by set screws 10. The fabric separating member 7 has a spring arm 11 which serves as a needle guide and also as fabric separating member. The arm 11 has a loop 12 formed by bending the spring under to 70 press on the cloth. The loop 12 has a slot 13 which serves as a needle guide.

The variation shown in Fig. 7 consists in making two loops 14 for adjusting purposes instead of one loop. The washer 4 is omitted from this view. The washer 4 may be placed diagonally across the loops to provide for greater variations. The thumb nut 3 is differently located on different machines. The variations in the loops 14 will 80 meet the requirements.

The variation shown in Figs. 3, 5, and 6 consists in using a holder which has two fabric separators 15 instead of one fabric separator, as in Figs. 1 and 4. This form 85 of holder and guide has two loops 12 instead of one loop.

The hemstitcher is held in place by the presser foot of the sewing machine and operates with the thumb screw 3. One piece 90 of cloth is placed on the bed of the machine under the springs 5 and 6 and 11. Then another piece of cloth is placed on top of the spring and needle guide 11 and under the springs 5 and 6 for operation.

What I claim, is,—

1. A hemstitcher comprising a body member having a pair of cloth holding springs disposed on opposite sides of a sewing machine needle and a loop for adjustably mounting said body on a sewing machine bed, means for fixedly attaching said loop to the machine bed, and a fabric separating member attached to said body member and having an arm provided with a slot for the passage of the needle and stitches and having bent under ends forming springs and located between said cloth holding springs.

2. A hemstitcher comprising a body member and means for attaching the same to a sewing machine bed, an arm integral with said body member and bent upwardly out

- of the plane of said body member and a pair of integral cloth holding springs in the plane of said arm and disposed on opposite sides of the sewing machine needle and 5 a pair of bent under springs disposed directly under the last named springs and co-operating therewith, and a fabric separating member attached to said body member and having an arm provided with a slot for the 10 passage of a needle and stitches and having bent under ends forming springs and located between said cloth holding springs.
3. A hemstitcher comprising a body member having a pair of cloth holding springs disposed on opposite sides of a sewing machine needle and a loop for adjust- 15

ably mounting said body on a sewing machine bed, means for fixedly attaching said loop to the sewing machine bed, a fabric separating member attached to said body 20 member and provided with an arm disposed between said cloth holding springs and having a slot for the passage of a needle and stitches and being adjustable longitudinally in the direction of said slot, and means for 25 attaching said fabric separating member to said body member at different points of adjustment.

In testimony whereof, I set my hand, this 28th day of November, 1924.

BENJAMIN F. GILBERT.
